To my kind & help over a Log bridge by which means
the water is passing through the Mill and the Mill
driven by the falling of water and the water being
current, and the entrance of the water into the Creek
from the river is to be regulated by opening & closing
gates in such manner that a gate or two may
when it is required to open or close a small dam
in the stream the gates shall be so properly placed
which will produce a difference in the level of the
water in the river and in the Creek, thus causing
a stronger current in the stream & the water
the gates will be open or closed as the water begins to
fill the dam operations as far as removing the
flood gates — What I desire as my payment
is a thick Creek stone & a good Pot
as well as the sum of one hundred

W. B. — James (Signed) — C. B. Moore
